UNITED STATES PATENT OFFICE.

SEIZI TADAKUMA, OF PORTLAND, OREGON.

SHOE.

1,139,598.

specification of Letters Patent. Patented May 18, 1915.

Application filed January 8, 1915. Serial No. 1,196.

To all whom it may concern:

Be it known that I, SEIZI TADAKUMA, residing at Portland, in the county of Multnomah and State of Oregon, have invented a new and Improved Shoe, of which the following is a specification.

This invention relates to improvements in footwear and it primarily has for its objects to provide a shoe so constructed that the wearer may readily adjust the upper or vamp portion thereof to properly fit upon the foot and which is especially adapted for use by those having corns, ruptured bones and other foot troubles.

It is well known that shoe uppers frequently wear out or break while the foundation of the shoe remains in a good condition, and often shoes are discarded by reason of the uppers being worn or broken while the shoe foundation remains good.

Among other objects, my invention seeks to provide an improved shoe in which the upper or vamp portion is so formed and attached to the shoe foundation that when worn out it may be readily removed from the said foundation and a new upper or vamp portion substituted therefor, or in other words, a shoe having the foundation or sole portion especially designed for being used in connection with what I term "alteration uppers", since the upper or vamp portions of my shoe, in practice, may be sold as a separate article and made of various kinds of leather or cloth and in sizes to suit the standard sizes of boots and shoes.

Another object of my invention is to provide an improved shoe that includes an upper or vamp portion readily applied around the sides and over the instep of the foot to suit the condition of the foot, and a flexible member that forms the substitute for the usual shoe tongue member, and which, in my construction of shoe, effectively serves to prevent water or dirt entering within the shoe.

Again my invention comprehends certain improvements in shoes, of the general character stated, that can be readily embodied in all types of men's, women's and children's footwear, high or low.

With other objects in view that will hereinafter appear, my invention consists of a shoe that embodies the peculiar construction and novel arrangement of the parts herein-after explained, specifically pointed out in

the claims, and illustrated in the accompanying drawings, in which:

Figure 1 is a perspective view of my improved shoe, the vamp or upper being shown unlaced and thrown back over the toe cap. Fig. 2 is a similar view that represents the front of the shoe with the upper unlaced. Fig. 3 is a perspective view of the shoe viewed from the back end, the tongue member being shown open and the upper or vamp portion unlaced. Fig. 4 is a side view of my improved shoe, the upper or vamp being in one piece. Fig. 5 is a view of the shoe with a vamp or upper portion formed of two pieces. Fig. 6 is a view of one of the vamp or upper sections. Fig. 7 is a side elevation of a high shoe or boot, a modified arrangement of the lacing or fastening means being also shown. Fig. 8 is a detail view that illustrates the manner in which the upper is secured within and to the toe cap of the shoe. Figs. 9 and 10 are detail views of modifications hereinafter referred to. Fig. 11 is a perspective view of the shoe, the upper and the body flange being provided with hooks and lace connections.

In the drawings, 1 designates the counter or quarter portion of the shoe body or foundation, the front edges of which form vertical lacing flanges 10-10 that merge with the oppositely disposed and forwardly extended lacing flanges 11 that extend from the vertical flanges to the toe cap 2, to which they are stitched, as indicated by 80.

5 designates the shoe sole and the same in my construction of shoe is attached to the counter 1 and the toe cap in the usual manner.

The flanges 10 and 11, in the form shown in Figs. 1 to 4, have lacing eyelets that extend the full length of the said flanges.

7 designates what I term a "tongue member", since the said member serves as a substitute for the ordinary shoe tongue member. In my construction of shoe, the tongue 7 is formed of a suitable flexible body, of leather, cloth or the like, and when applied for use, the lower front end of the said body extends under and is sewed to the toe cap 2, while the side portions of the said body are stitched to the lacing flanges 10 and 11 of the shoe, as is clearly shown in the drawing. By connecting the member 7 to the shoe body, as stated, it follows that the said body forms the pocket into which the foot of the wearer is received and serves as a means for

incasing the entire foot and thereby keeping water or dirt out of the shoe. To provide for a perfect or tight fit of the member 7 over the sides and instep of the foot, the said member 7 may be slit to form two opposing flaps 70 (see Fig. 5) which, when putting on the shoe, are readily lapped upon themselves and over the instep of the foot before the vamp or upper portion, presently described, is finally closed over and about the foot.

8 designates the vamp or upper portion of my improved shoe and the same is preferably a single piece that is cut to a shape to fill the space between the opposite lacing edges of the body 1 and the toe cap 2, and the said vamp or upper member 8, is fixedly connected to the shoe body at its front end only, the said end being projected into the toe cap and sewed thereto by stitching, as is best shown in Figs. 1 and 8. By referring to the said Figs. 1 and 8, it will be also noticed that the lacing flanges 11 are disposed close to the shoe sole and that the sides of the tongue member 7 are stitched to the said flanges 11 and to the straight or vertical flanges 10.

The lower or front end 73 of the member 7 that extends under the toe cap is secured by the stitching 80 that also secures the front end of the vamp or upper 8, as is best shown in Fig. 8 of the drawing.

In those forms of my shoe in which the meeting edges of the upper and the edges 10 and 11 are joined by laces, the lacing edges 83 of the member 8 are shaped to fit closely up to the side edges 10 and 11, but when the said edges 10 and 11 and 83 are secured by buttons, as shown in Fig. 9, the edges 83 lap over the edges 10 and 11, see Fig. 9.

It should be stated that the fastening means for closing the shoe may be composed of eyelets that extend the full length of the edges 10, 11 and 83, through which laces 45 may be passed (see Figs. 5 and 6); or eyelets may be provided along the edges 10, 11 and 83 on one side of the shoe and eyelets along the lower part of the edges 83 and 11 on the other side of the shoe and hooks 84 for the upper part of the edges 83 and 11 on said other side of the shoe, as shown in Fig. 10; or hooks may be provided on the edges 10, 11 and 83 on both sides of the shoe, as shown in Fig. 11; or buttons may be provided, as indicated in Fig. 9; or eyelets and hooks, as indicated in Fig. 7; as may be desired.

To keep the laces and buttons from contacting with objects the sole of the shoe may be made somewhat wider than is usual, see Fig. 8; it being, however, understood, that in the make-up of my improved shoe, the standard widths of the sole may be maintained.

From the foregoing, taken in connection

with the accompanying drawings, the complete construction and the advantages of my improved shoe will be readily apparent.

By reason of forming the shoe with an upper or vamp portion shaped as shown, 70 fixedly connected to the shoe foundation at the front end only, and shaping the opposite edges and the coincident edges of the counter or body of the shoe, as stated, the uppers may be changed readily any number of times, and the shoe used until the foundation is beyond further re-use, and since the upper is sewed at the front end only to the shoe cap it can be easily removed and a new one substituted. Again, 80 by extending the lacings at each side of the shoe downwardly from the top, in a substantially vertical direction and thence extended forwardly in a plane substantially 85 parallel with the shoe sole and located adjacent the welt, the said lacing connections follow the shape of the foot from the ankle along the heel and thence forwardly, and by reason thereof, the upper can be quickly 90 and properly fitted upon the foot to suit the 95 conditions of or exact shape of the foot, by lacing tightly at some points and correspondingly loosely at other points, on either or both sides of the foot. Furthermore by forming the upper or vamp portion 8 in 95 the manner shown and described and lacing the same to the foundation of the shoe, as stated, provision is made for the variations of width, height and length of the 100 instep portion of the shoe, to avoid pressure on the instep of the foot and to so hold the upper or vamp that it readily gives or yields in any direction while walking, it being understood that the inside member 7 keeps the foot entirely incased at all times and 105 water and dirt that might enter between the laced edges from getting inside of the shoe, it being also apparent that since the entire upper can be readily thrown back, the same can be readily cleaned, and as it 110 is secured at both sides of the shoe, only one side need be unfastened, when removing the shoe from the foot.

What I claim is:

1. A shoe construction, comprising a 115 foundation that includes a counter or quarter portion having opposite front edges and a toe cap, a flexible member having its side edges secured to the opposite edges of the counter portion and its front edge to the 120 toe cap, and a vamp or upper section fixedly connected to the toe cap only, the said vamp or upper section being shaped to fit the space between the opposite sides of the counter portion, and means for holding the 125 adjacent edges of the vamp or upper section and the counter portion closed against each other.

2. A shoe comprising a foundation that 130 includes a shoe counter or quarter portion,

a sole portion and a toe cap, said counter portion having opposite edges extending downwardly in a substantially vertical plane to a point near the sole portion of the 5 foundation and thence forwardly to the toe cap in a plane substantially parallel with the said sole portion, a flexible member having its side edges secured to the opposite edges of the counter portion and 10 having its front end secured to the toe cap and an upper or vamp member having a shape to fit over the said flexible member with its side edges adjacent to the opposite side edges of the counter portion, the front 15 end of the said vamp extending under the toe cap and being secured to the said toe cap, and means for joining the adjacent edges of the vamp or upper portion and the counter portion to hold them in a closed 20 relation.

3. In a shoe of the character stated, a

foundation that includes a sole portion, a toe cap, a counter portion whose upper front edges are extended downwardly to a point near the sole portion of the shoe, and a 25 flexible member whose opposite side edges are fixedly connected to the front edges of the counter portion and whose front end is fixedly joined to the toe cap, a vamp or upper section having a shape to fit over the 30 flexible member and within the space between the opposite edges of the counter portion, means fixedly securing the lower front end thereof to the underside of the toe cap and other means that coöperate with the adjacent edges of the counter portion and the vamp or upper portion for holding the said edges in a closed relation. 35
